UNITED STATES PATENT OFFICE

2,212,516

SHOE AND METHOD OF MAKING THE SAME

Karl Engel, Swampscott, Mass., assignor to United Shoe Machinery Corporation, Borough of Flemington, N. J., a corporation of New Jersey

Original application September 8, 1936, Serial No. 99,691. Divided and this application November 8, 1939, Serial No. 303,445

4 Claims. (Cl. 12—142)

This invention relates to shoes and methods of making the same.

It is an object of the present invention to apply the shoe bottoming principles set forth in my co-pending application Serial No. 99,691, filed September 8, 1936 to the manufacture of a shoe the upper of which has the general characteristics of a Blucher type shoe. This application is a division of my application above referred to.

With the above object in view, the invention in one aspect thereof and as disclosed herein comprises a method of making shoes which consists in providing an upper having top and bottom openings both of which extend substantially the full length of the upper, providing a tongue and a toe stiffener, arranging the tongue to extend from the interior of the upper at a point adjacent to the bottom margin of the upper at its toe end heightwise of the upper to its top margin, and then generally lengthwise of the shoe toward its heel end, securing the tongue to the top margin of the upper, positioning the toe stiffener between the tongue and the inner surface of the toe end of the upper, turning the bottom margin of the upper inwardly and securing said margin to a sole.

The invention also includes a shoe which may be produced by the above method and is characterized by a seam whereby the bottom margin of the stiffener is stitched to the bottom margin of the tongue to hold it against displacement.

The invention will now be described with reference to the accompanying drawing and pointed out in the appended claims.

In the drawing,

Fig. 1 is a plan view of a shoe embodying the features of the present invention;

Fig. 2 is a section on the line II—II of Fig. 1; and

Fig. 3 is a perspective view of the shoe illustrated in Fig. 1.

Referring to Fig. 1 the illustrated shoe comprises a vamp 10 the top of which is open substantially throughout its entire length and is provided with a tongue 12 which is about the same length as the vamp. The vamp is stitched to a quarter 14 which has the same general shape as the rear part of a pump or slipper. The bottom margins of the vamp and the quarter are turned inwardly and stitched to a sole 16 which is here illustrated as the tread sole of a single sole shoe. The vamp and the quarter are so patterned that the general shape of the shoe is obtained by turning the bottom margin of the upper inwardly and stitching it to the margin of a sole in predeter-

mined relation thereto. In the illustrated shoe, the inturned margin is located relatively to the sole by positioning it in a marginal recess provided in the sole and locating the edge face of the upper against the inner wall of the recess. (See Fig. 2.)

The illustrated shoe is provided with a toe stiffener such, for example, as the stiffener 18 illustrated in Fig. 2 which is located between the toe end 20 of the vamp 10 and a downward extension 22 of the tongue 12. The toe stiffener is cemented to the adjacent surfaces of the vamp and to the downward extension of the tongue and the bottom margin of said stiffener is preferably secured to the bottom margin of the tongue by a seam 24. The toe stiffener may be formed from any suitable material. Sole leather, for example, has been found to be suitable for toe stiffeners of this type. The entire margin of the toe stiffener 18 is skived in order to avoid the formation of objectionable irregularities in the upper along the margin of the stiffener.

In the manufacture of the illustrated shoe, the toe stiffener 18 is secured to the bottom margin of the tongue 12 by the seam 24 and thereafter the top seam 26 is formed in the vamp and as the stitching of the top seam progresses across the toe end of the vamp the tongue 12 with the toe stiffener secured thereto is stitched to the toe end of the vamp. The toe end of the vamp then is turned upwardly away from the toe stiffener and the toe stiffener in turn is turned downwardly from the tongue in order to permit both sides of the stiffener and the adjacent surfaces of the tongue and the vamp to be coated with cement. After the cement has been applied, the parts are returned to their initial position and bonded together in their relation to one another illustrated in Fig. 2. The bottom margin of the upper is then turned inwardly and positioned in the marginal channel in the sole 16 with its edge face against the inner wall of the channel and secured thereto by a sewn seam 28.

Having thus described my invention, what I claim as new and desire to secure by Letters Patent of the United States is:

1. That method of making shoes which comprises forming an upper with top and bottom openings extending substantially the full length of the upper, arranging a tongue to extend from the interior of the shoe bottom at its toe end heightwise of the upper to the top of the toe end of the upper and then generally lengthwise of the upper toward its heel end, securing the tongue to the top margin of the toe end of the

upper, positioning a toe stiffener between the tongue and the inner surface of the toe end of the upper, turning the bottom margin of the upper inwardly, and securing said margin to a sole.

2. That method of making shoes which comprises forming an upper with top and bottom openings extending substantially the full length of the upper, providing a tongue of approximately one-half the length of the upper, securing a toe stiffener to the outer surface of the toe end of the tongue by a sewn seam extending through the adjacent margins of the tongue and the stiffener, arranging the tongue with the stiffener secured to it to extend from the interior of the upper to the top of the toe end of the upper, then generally lengthwise of the upper toward its heel end, securing the tongue to the top margin of the toe end of the upper, turning the bottom margin of the upper inwardly, and securing said margin to a sole.

3. That method of making shoes which comprises forming an upper with top and bottom

openings extending substantially the full length of the upper, arranging a tongue to extend from the interior of the shoe bottom at its toe end heightwise of the upper to the top of the toe end of the upper and then generally lengthwise of the upper toward its heel end, securing the tongue to the top margin of the toe end of the upper, positioning a toe stiffener between the tongue and the inner surface of the toe end of the upper, turning the bottom margin of the upper inwardly, positioning the inturned margin of the upper in a marginal channel in the upper surface of a sole, and stitching the inturned margin to the sole with its edge face abutting the inner wall of said channel.

4. A shoe having a tongue one end of which extends into the interior of the toe end of the upper, and a toe stiffener positioned between the interior of the toe end of the upper and the adjacent surface of the tongue, the bottom margin of the stiffener being stitched to the bottom margin of the tongue.

KARL ENGEL.
